(57) **CLAIM**

I claim the ornamental design for a magnetic clip device, as shown and described.

DESCRIPTION

FIG. 1 is a perspective view of a magnetic clip device embodying the design from a first angle.

FIG. 2 is a perspective view of the magnetic clip device of FIG. 1 from a second angle.

FIG. 3 is an end view of the magnetic clip device of FIG. 1.

FIG. 4 is a side view of the magnetic clip device of FIG. 1.

FIG. 5 is a front view of the magnetic clip device of FIG. 1; and,

FIG. 6 is a back view of the magnetic clip device shown in FIG. 1.

1 Claim, 2 Drawing Sheets

FIG. 2

FIG. 1

FIG. 3

FIG. 4

FIG. 5

FIG. 6
